[57] **CLAIM**

The ornamental design for a measuring gauge for wrench sizing, as shown.

DESCRIPTION

FIG. 1 is a top plan view of a measuring gauge for wrench sizing showing our new design, the bottom plan view being identical;

FIG. 2 is a right side elevational view, the left side elevational view being identical;

FIG. 3 is a top plan view of an embodiment of our new design of FIGS. 1 and 2, the bottom plan view being identical; and

FIG. 4 is a right side elevational view thereof, the left side elevational view being identical.

FIG.1.

FIG.2.

FIG.3.

FIG.4.
